United States Patent Office

Des. 180,939
Patented Sept. 10, 1957

180,939

COMBINED CAMERA AND FLASH GUN HOLDER OR SIMILAR ARTICLE

Norman E. Elsas, Atlanta, Ga.

Application December 5, 1956, Serial No. 44,072

Term of patent 14 years

(Cl. D61—1)

FIG. 1

FIG. 2

FIG. 3

Fig. 1 is a side elevational view of a combined camera and flash gun holder or similar article, showing my new design;

Fig. 2 is a top plan view; and

Fig. 3 is a perspective view thereof.

The broken line showings of a camera and flash gun are for illustrative purposes only.

I claim:

The ornamental design for a combined camera and flash gun holder or similar article, as shown and described.
